UNITED STATES PATENT OFFICE.

RICHARD MOHLER AND JOHN BECKER, OF LANCASTER COUNTY, PA.

IMPROVEMENT IN FLOUR-BOLTS.

Specification forming part of Letters Patent No. 39,826, dated September 8, 1863.

To all whom it may concern:

Be it known that we, RICHARD MOHLER and JOHN BECKER, both of Lancaster county, in the State of Pennsylvania, have jointly invented a new and improved mode and arrangement of knockers or beaters operating externally against the reels or flour-bolts used in grist-mills; and we do hereby declare that the following is a full and exact description thereof, reference being had to the accompanying drawings, making a part of this specification, with the letters of reference marked thereon.

Figure 1 is a perspective view of the bolting-chest A, open lid L, showing the lower portion of the bolting-reel and cloth B, external ribs C, rail D, on its end support, E, with a series of poised levers or beaters, F, in place. Fig. 2 shows the arrangement of the beaters detached; Fig. 3, a single beater raised out of its slot d in the rail D, (shown in part,) with the upper long groove, g, in which the pin G or pivot of the beater F is lodged, and on which it has its vibrating motion. This pivot can be set through any one of a double series of holes, h, shown.

The construction is as simple as its operation and readily understood by the drawings. The bolt is of the ordinary kind in use, and the only addition thereto is a partial rib over each beater, or a single rib along the entire length of the bolt, applied over each angle on the outer surface. These ribs c are raised from the cloth and inner rib of the reel by means of filling or washers of any desired thickness around each screw, nail, or bolt employed. This prevents cutting the cloth and aids the vibrating action of the beaters. The end supports, E E', for the rail D, and its beaters or levers F may also be made adjustable for elevating or lowering the rail by slots and screws through the ends of the bolting-chest, or affixed permanently at the proper height. The rail D can be drawn in or out beneath the bolt, sliding on the end pieces, adjustable to any position most desirable with the vibrating beaters or lever-knockers F, so poised that the revolutions of the bolt will bring each of its external ribs, c, in contact with the entire series as to depress the inner ends, f, of the levers F. The outer ends being weightier will necessarily drop the moment the reel or rib of the bolt passes over and releases the same, causing the levers to

strike upward against the succeeding ribs in quick succession as the bolt revolves over them. The force of the beaters or levers is easily regulated by changing the fulcrum or pin from one hole to another in the lever; and, as said beaters set in a slot, d, on the top of the rail D, and the pins G fit into a groove, g, on the top of the rail, which holds them in place, it follows that each lever F can be taken from its place and replaced after adjusting the pin without interfering with or stopping the bolting, thus affording a wide range of adjustment to a single beater or to the entire series with the greatest ease to produce any desired amount of force in the upward stroke—this together with the fact that a blow or concussion on the outside of the reel or bolt and at its lower point is more efficacious in producing the result to be accomplished by knockers than when the concussion is in any manner produced within the bolt, to say nothing of the difficulty of getting at them in order to regulate the same, which requires the interruption of the bolting at best when effected by any arrangement employed now in use. This position and arrangement of the beaters is deemed a decided improvement, and greatly facilitates the process of bolting. A little reflection upon the law governing concussions cannot fail to convince the mind, what actual experiment has clearly proved, that a blow struck on the outside, beneath the bolt, where the meal is lodged and discharged, is the proper and most effectual point for producing the desired result. Flour, like dust, reacts in the direction from whence the blow comes, especially if the opposite side affords any elastic resistance—such, for instance, as your thigh under the cloth of your pantaloons—a blow with your hand will bring the dust concealed in the meshes of the cloth to the surface. This fact is readily demonstrated, hence no further argument is required. Besides, a blow on the top of the bolt, where it is empty, although it clears the meshes by discharging the flour both without and within the bolt, scattering it in every direction within the bolt and bolting-chest, much of which again settles both on the outer and inner surface of the bolting-cloth, and more or less again clogs the same in its revolution before the previously-cleared surface comes to the discharging-point, thus losing the efficacy of

the concussion to a great degree, whereas a blow beneath simultaneously with the dropping of the flour greatly augments its discharge. This arrangement is also as cheap and simple of application as it is efficient in its operation.

What we claim as our invention, and desire to secure by Letters Patent, is—

The arrangement of a series of levers or beaters, F, made adjustable separately or col-

lectively by means of the holes h, pins G, rail D, and end supports, E, operating substantially in the manner specified against the under surface of the reel, as shown.

RICHD. MOHLER.
JOHN BECKER.
